UNITED STATES PATENT OFFICE

2,594,195

DRIVING MECHANISM FOR MINING MACHINES

Myron G. Miller, Springs, Pa.

Application April 5, 1949, Serial No. 85,498

4 Claims. (Cl. 262—22)

1

The present invention relates to improvements in driving mechanism for coal undercutting machines and more particularly to an improved drive for a machine such as is illustrated and described in Patent No. 2,094,218, issued to Gideon D. Miller on September 28, 1937.

The drive arrangement of the aforementioned patent was developed to not only rotatably drive the usual forwardly extending augers, but also to develop a power drive for the ground engaging wheels for supporting the machine to move it to different locations. This transportation arrangement has proven very desirable. However, these machines are very dangerous to move from one location to another, particularly under their own tractive power as heretofore there was no means provided to discontinue the operation of the augers during transmission of driving power to the ground wheels for movement to another location.

It is, accordingly, an object of this invention to provide a novel drive for the augers of a coal undercutting machine, whereby the power to the augers and the ground wheels may be selectively and independently controlled, so that one or the other may be rendered inoperative as desired by an operator.

Another object is to provide in an undercutting machine, comprising a bank of aligned cutting augers, a centrally proportioned auger clutch control and an adjacently mounted traction wheel clutch control drive adapted to both be independently driven from the same main reduction gear drive.

With these and other objects in view, the invention consists in the construction, arrangement and combination of parts hereinafter described and particularly summarized in the appended claims.

In the drawings like parts throughout the several views are given like numerals and are thus identified in the following detailed description.

Fig. 1 is a top horizontal cross sectional view of a machine for undercutting coal showing the separate auger and traction wheel drives and the novel arrangement for connecting and disconnecting the same for independent operation.

Fig. 2 is a side elevational view of the machine showing a portion of the forward projecting augers.

Fig. 3 is a front elevational view of an interconnecting gear train mounted in a spacer plate for driving connection between the shaft extensions of the central auger and the shaft extension of an adjacent side auger for key-mounting

2

the combined beveled gear and clutch for the drive to the ground wheels.

Fig. 4 is an exploded view of the drive gears and auger shaft for the auger drive and clutch arrangement.

Fig. 5 is an exploded view of the drive gears and second auger shaft extension of one of the side augers for the traction wheel gear drive and clutch arrangement.

Referring in detail to the several views of the drawing and first with particular reference to Fig. 1, the drive unit for the augers 9 is generally indicated by A and the adjacent drive for the traction wheels of the machine is generally indicated by B. These two drives are operatively connected through means of gears 10, 11, 12 and 13 mounted in a spacer plate on the machine frame. Each of these gears is connected to a portion of one of the auger shafts as will now be explained.

The first of these gears 10, see both Figs. 1 and 4, is formed with a sleeve 14 to which is keyed a main drive gear 15 by means of a key 16. This gear 15 is formed with a set of clutch teeth 17 on its side face opposite from the gear 10 and is driven by a chain sprocket drive 18 actuated by a motor 19, see Fig. 2. This chain and sprocket drive is connected by a shaft 20 to reduction gearing such as is clearly illustrated in Fig. 5 of the Miller Patent No. 2,090,355, dated August 17, 1937.

The sleeve 14 and the main drive gear 15 are mounted on an extension of a centrally located auger shaft 21 to the lower end of which is keyed a splined sleeve 22 by means of a key 23. On this splined sleeve 22 is mounted a clutch collar 24 formed with similar splines on its internal bore to interengage with those formed on the exterior to said sleeve 22. The clutch collar 24 is formed with clutch teeth 25 which are adapted to interengage with the clutch teeth 17 formed on the face of the main gear 15.

A retaining cup 26 formed with an opening fits over the end of this auger shaft extension which at its top end is reduced to form a shoulder 27 and abuts against this shoulder.

To retain the cup in position against shoulder 27 there is provided a conical bushing 28 which is the inner race of a ball bearing 28a held in place over the said reduced end by a clutch actuator support member 29 formed with elongated grooves extending axially with respect to the axis of the auger shaft 21. These grooves are adapted to receive clutch actuating arms 30 and 31 formed with hooked ends which project into an annular

groove 34 around the circumference of the clutch sleeve 24. The ends of the arms 30 and 31 project beyond the bottom of the member 29 and are connected together by a cross bar 35. This bar is formed intermediate its ends with a ball socket for the purpose of receiving the ball connection 36 of the clutch actuating rod 37. The clutch rod 37 is rocked by means of lever 38. Rocking of rod 37 will raise and lower the arms 30 and 31 in the groove and thereby longitudinally move the clutch sleeve 24 along the splined sleeve 22 to connect and disconnect the cooperative clutch teeth 25 thereof with the teeth 17 on the main drive gear 15.

The idler gear 11 is in mesh with gear 10 and is mounted loosely on a stub extension 40, see Fig. 1, of the adjacent auger shaft. Gear 11 also meshes with the similarly mounted idler gear 12 which is also on a stub shaft extension 41 of the next aligned auger shaft. This gear 12 in its turn meshes with the last of the four gears, namely, gear 13 of the traction drive unit B.

The gear 13 is formed with a sleeve extension 44 and is loosely mounted on an extended portion 42 of the next auger shaft in line. This extended sleeve portion is formed with longitudinal splines 44, see Fig. 5, for the purpose of receiving an internally splined clutch sleeve 46. The sleeve 46 is provided with clutch teeth 47 on its face opposite from the gear 13 and is formed with an annular groove similar to that of clutch sleeve 24 to receive end hooked arms 52 and 53, which are actuated by hand lever 54 in the same manner as described in connection with the end hooked arms 30 and 31.

Abutting against the end of the splined sleeve 46 is a clutch plate 49 of a transmitting bevel gear 48, which gear is loosely mounted to revolve on a reduced end of the auger shaft extension 41 and is held against longitudinal thrust by lock washer 49^a and nut 49^b.

Thus, normally when power is imparted from the main drive gear 15 and gear 10 or sleeve 14 through idler gears 11 and 12 to drive gear 13, this gear 13 will idly turn on the extension 41 without imparting any drive to the bevel gear 48. This is provided it is not clutched with the clutch teeth 50 formed on the plate 51 formed on the top of said bevel gear 48.

The bevel gear 48 meshes with bevel gears 55 and 56 mounted upon a jack shaft 57, see Fig. 1. The jack shaft 57 is supported between a side plate 58 and a bearing support 59. Also, the bevel gears 55 and 56 are rotatable in opposite directions, the gear 55 being used as the reverse and the gear 56 used as the forward driving gear for the traction drive shaft 60.

The traction wheel drive shaft 60 has the same gear members for imparting drive to the sprocket wheels 61 and 62 keyed to opposite ends thereof as in Patent No. 2,094,218. For example, the counter shaft 60, as it is defined in this patent application, extends transversely of the machine and beyond the side plate 58 of each side and is journaled in these plates in bearing supports to serve as mountings for the sprocket wheels 61. The sprocket wheel on each extended end of the counter shaft drives a sprocket chain 63 and a relatively large sprocket wheel 64 keyed to the traction wheel axle 65.

The gears for the forward drive of the traction wheels 66 take-off from bevel gear 55 through gear wheel 67 revolving with it on the jack shaft 57 and drives a gear 68 mounted to revolve on the counter shaft 60. A gear 69 revolves with gear

68 on counter shaft 60, and gear 68 in turn drives gear 70 on the jack shaft 57. Turning with gear 70 is the gear 71 which drives the gear 72 revolvable upon the countershaft 60 and also with respect to the gear 68.

Gears 68 and 72 are formed on their respective outer faces with toothed hubs 73 and 74, respectively, which hubs are slidable on a splined portion of the shaft 60 to provide for forward and reverse driving connections to the drive chains 63 and traction wheels 66, as illustrated and described in Patent 2,094,218.

Operation.

15 The improved machine of the present invention may now be driven under its own power to and from mine locations without the dangerous continued rotation of the forwardly extending augers 9. For example, when the clutch member 24 is de-clutched from the clutch teeth 17 of the main drive gear 15 there is no drive imparted to the auger shaft extension 21. This is because the sleeve 14, which carries the gear 10 and to which the drive gear 15 is keyed, is loose on the shaft extension 21 and rotates freely thereon unless clutched to the splined sleeve 22 keyed to the shaft 21.

Drive, however, is transmitted from gear 10 through gears 11, 12 and 13 to sleeve 44 and clutch sleeve 46 splined thereon. Now, when the clutch 46 is actuated by lever 54 to engage the clutch teeth of bevel drive gear 48 power is imparted to gears 55 and 56, which gears, as explained, may be alternately clutched into either forward or reverse driving connection with the countershaft 60 to actuate the chain drives of each of the ground wheels 66 and the machine is thus transportable with the augers idle.

Obviously, to start the auger 9 in action all that is necessary is to engage the clutch 24 with the teeth 17 on the main drive gear 15. This imparts drive through the splined sleeve 22 keyed directly to the shaft extension 21. When the augers are started the traction power mechanism B may be de-clutched and the several gears, 11, 12, 13, sleeve 44 and clutch 46 rotate but do not transmit power. Also, if desired, the ground wheels may be regulated to provide traction while the augers 9 are in action by throwing in the clutch by lever 54.

Without further description it is thought that the features and advantages of the invention will be readily apparent to those skilled in the art, and it will of course be understood that changes in the form, proportion and minor details of construction may be resorted to without departing from the spirit of the invention and scope of the appended claims.

I claim:

1. In an undercutting mining machine having a plurality of forwardly projecting power driven augers and power driven ground wheels, independent drive means for said augers and said ground wheels, each of said drive means being mounted on a rearwardly projecting shaft extension of one of the said augers, one of said shaft extensions mounting a main power gear, an auger drive gear and a clutch, a gear train driven by said main power gear adapted to impart power to said other drive means mounted on the second auger shaft extension, said second auger shaft extension mounting a combined ground wheel drive gear and clutch member for imparting power to said ground wheels, a second clutch member rotatable by said gear train and

main power gear, and clutch actuating means for connecting said combined clutch and wheel drive gear into driving connection with said gear train through said second clutch member independently of said auger drive gear.

2. In a coal undercutting machine having a frame, ground engaging wheels mounted on each side of the frame, a plurality of forwardly extending augers and means for operating the augers, said means comprising a rearwardly extending shaft from one of the augers, a gear formed with a sleeve rotatable on the shaft, a source of power, a power driven gear keyed to the sleeve driven from said power source, clutch teeth formed on a face of said power driven gear, a clutch member slidable into and out of engagement with said clutch teeth for driving the said augers, and means for imparting power to said driving wheels from said power driven gear.

3. In a coal undercutting machine having a frame, ground engaging wheels mounted on each side of the frame, a plurality of forwardly extending augers and means for operating the augers, said means comprising a rearwardly extending shaft from one of the augers, a gear formed with a sleeve rotatable on the shaft, a source of power, a power driven gear keyed to the sleeve driven from said power source, clutch teeth formed on a face of said power driven gear, a clutch member slidable into and out of engagement with said clutch teeth for driving the said augers, means for driving said ground wheels, and a gear train mounted to revolve in said frame for im-

parting power from said power driven gear to said last named means for driving said ground wheels.

4. In a coal undercutting machine having a frame, ground engaging wheels mounted on said side of the frame, a plurality of forwardly extending augers and means for operating the augers, said means comprising a rearwardly extending shaft from one of the augers, a gear formed with a sleeve rotatable on the shaft, a source of power, a power driven gear keyed to the sleeve driven from said power source, clutch teeth formed on a face of said power driven gear, a clutch member slidable into and out of engagement with said clutch teeth for driving the said augers, means for driving said ground wheels, a gear train mounted to revolve in said frame for imparting power from said power driven gear to said last named means for driving said ground wheels, and manually controlled clutch means for rendering the said last-named means inactive, if desired, to drive the ground wheels.
